UNITED STATES PATENT OFFICE.

HOWARD M. DUDLEY, OF PHILADELPHIA, PENNSYLVANIA.

DYEING-MACHINE.

1,266,108.

Specification of Letters Patent. Patented May 14, 1918.

Application filed April 6, 1917. Serial No. 160,114.

To all whom it may concern:

Be it known that I, HOWARD M. DUDLEY, a citizen of the United States, and a resident of Philadelphia, in the county of Philadelphia and State of Pennsylvania, have invented certain new and useful Improvements in Dyeing-Machines, of which the following is a specification.

My invention relates to a dyeing machine and refers particularly to a machine adapted for the dyeing of textile fibers compressed within a dyeing chamber, the dyeing being accomplished by the forced passage of the dye liquor through the fiber mass.

Among the objects of my invention is a dyeing machine particularly suitable for the dyeing of warps in the ball, whereby the condition of the fiber may be accurately and readily judged at any stage of the treatment without opening the dyeing chamber and whereby even results may be obtained without disturbing the fiber to be dyed.

Another object of my invention is a dyeing machine in which the dyed goods may be after-treated with water, steam, air, or other materials or substances without handling the dyed goods, and whereby a series of batches of fiber may be treated simultaneously.

Other objects of my invention will be evident upon a consideration of my specification and claims.

I have found that the even or uneven dyeing results obtained in a machine of this general character depend largely upon the particular shape of the openings through which the dye liquor enters the fiber mass, and that unevenness can be prevented by the use of openings of a particular shape, the conformation of which enables the liquor to spread itself through the fiber mass without the formation of channels of flow.

I have further found that this desirable result may be enhanced by inclosing the fiber in a series of containers and passing the treating liquid through these containers and the fiber contained therein, first in one direction and then in the reverse direction.

In the use of many dyestuffs it is necessary, after dyeing to treat the dyed goods with water for washing purposes, or with solutions of chemicals such as metallic salts or oxidizing products, for the purpose of

after-treatment, or with oxygen or air for oxidizing or drying purposes. In the following of these after-treatments it is essential that every portion of the dyed goods be thoroughly and uniformly treated and that the operation be performed as readily and quickly as possible. All of these results are obtainable by the use of the device of my invention, in which the goods are placed in the dyeing chamber and then rapidly, easily and completely dyed and after-treated without further handling of the goods and without the formation of channels by the liquids employed. The device therefore insures even and uniform results with a minimum of time, labor and expense.

One form of my device is shown in the accompanying drawings in which similar parts are designated by similar numerals.

Figure 1 is a top plan view of one form of the device of my invention.

Figs. 1^A and 1^B illustrate certain pipe connections carried by the chambers of the pumps.

Fig. 2 is a side plan view of a portion of Fig. 1, partly broken away.

Fig. 3 is a side plan view of a portion of Fig. 1, partly broken away, and showing the device in position for loading and unloading.

Fig. 4 is a cross-section of one of the members showing the plates.

Fig. 5 is a top plan view of Fig. 4.

Fig. 6 is a cross-section through the line 6—6 of Fig. 2.

Fig. 7 is a cross-section through the line 7—7 of Fig. 6.

Fig. 8 is a cross-section through the line 8—8 of Fig. 2.

Fig. 9 is a fragmentary enlarged cross-section of one of the foraminous end plates.

Fig. 10 is a face view of Fig. 9, in the direction of arrow 10.

Fig. 11 is a fragmentary enlarged cross-section of one of the intermediate foraminous plates.

Fig. 12 is a face view of Fig. 11, in the direction of arrow 12.

In the form of my device as illustrated in the accompanying drawings, the truck 20 is mounted upon the wheels 21, 21, which are capable of movement upon the tracks 22, 22. Pivotedly mounted upon the truck 20, is a receptacle 23, fixedly attached to

the pinion 24 which is revoluble within the frame 25. Fixedly attached to the pinion 24 is a toothed segmental wheel 26, meshing with the teeth of the worm 27. The worm 27 is revoluble within the supports 28, 28, mounted upon the truck 20 and is capable of revolution by revolving the wheel 29 fixedly attached to the shaft 30 of the worm 27. The turning of the wheel 29 therefore 10 revolves the receptacle 23 through the medium of the worm 27 and the toothed wheel 26. The receptacle 23 is comprised of the shell 31 to which is fixedly attached a series of outwardly extended shoulders 32, 32 positioned near one end of the shell 31. Extending across the shell 31 and removable therefrom is a fiber-holding tray 47 having a foraminous plate 33. The pipe 34, 35 is attached to the shell 31 to coincide with an 15 opening therein, and carries the coupling 36 and the valve 37. The pipe 35 opens into the top of a liquid reserve tank 38. A smaller apparatus 39, the interior arrangement of parts of which is similar to the interior arrangement of parts of the receptacle 23, is connected to the interior of the receptacle 23 by means of the conduits 40, 40^A within the shell 31 carrying respectively the valves 41, 41^A, the interior of the apparatus 39 being connected to the top of the reserve tank 38 by means of the pipe 101. The testing device 39 is connected to the valves 41, 41^A by means of couplings to allow the testing device to be removed from engagement therewith. A thermometer 42 is introduced into the pipe 34. Perforated steam pipes 43, 43^A are within the receptacle 23. A pipe 83, carrying the valve 84 opens into the interior of the receptacle 23 for drawing the liquid from said receptacle. The interior of the receptacle 23 carries a series of movable fiber-holding trays 44, 45, 46. Each of the fiber-holding trays 44, 45 and 46 is comprised of a foraminous bottom 33 to 45 which are fixedly attached a series of lugs 49, 49 and a side member 50 integral with the foraminous plate 33 extends upwardly to the top of the lugs 49, 49, said side member 50 being integral with and fixedly attached to the interior faces of the lugs 49, 49. The lugs 49, 49 are vertically movable within the lug-chambers 51, 51 of the shell 31. The interior of each of the fiber-holding trays 44, 45 and 46 is therefore 50 formed by the foraminous bottom 33 and the side member 50. The lugs 49, 49 of all of the fiber-holding trays carry holes 52, 52 with inserted pins 100, 100 for the insertion of withdrawal means as hereinafter 55 described.

Each of the two end foraminous bottoms 33, 33 is composed of a series of parallel semi-circular adjacent bars 53, 53, each bar carrying a series of upwardly extended 60 pointed members 54, 54, with openings 55,

55 between said series of pointed members in order to allow the passage of liquid therethrough.

Each of the intermediate foraminous bottoms is composed of a series of spaced cylindrical bars 56, 56 carrying series of upwardly and downwardly extended pointed members 57, 57, liquid being free to pass through the openings 58, 58 between the bars 56, 56. 75

An annular member 67 is extended into members 68, 68 capable of abutment upon the lugs 49, 49 of the end fiber-holding tray 46. The member 67 can be movably attached to the arms 32, 32 of the shell 31 by the screw-bolts 69, 69. 80

The fiber-holding member 103 is formed the same as the fiber-holding members 44, 45, 46, 47 except that it has no side member 50. 85

At the two ends of the receptacle 23 are the hollow members 64, 64^A extended into the hollow members 65, 65^A. The larger end of each of the members 64, 64^A is of the same size and shape as the end of the receptacle 23, upon which it is capable of abutment, and carries the angular collars 66, 66^A, capable of engagement with the annular member 70 of the receptacle 23, and the flange 95 of the shell 31, thus allowing tight 95 engagement between the members 64, 64^A and the receptacle 23. 90

The method of attaching the members 64, 64^A to the shell 31 of the receptacle 23 is as follows, as shown in Figs. 2 and 8: A compressible gasket 82, 82 is inserted between the pyramidal shaped flange members 66^A and 95, the gasket being preferably formed of a number of pieces. The clamping member 59 is closed upon its hinge 60, the inclined inner faces of the clamping member abutting upon the inclined outer faces of the flange members 66^A and 95, and the joint between the two flange members made tight by the pressure carried by means of the thumb-screw 61. The dotted lines of Fig. 8 show the clamping member 59 in its open position, the joint between the flange members 66 and 70 being made in a similar manner. The centrifugal pumps 71, 71^A are connected at their discharge ends with the members 65, 65^A by means of the pipes 90, 90^A. The charging ends of the pumps 71, 71^A are connected with three-way pipes 73, 73^A, which three-way pipes are connected with the pipes 74, 74^A carrying the valves 75, 75^A, the pipes 76, 76^A carrying the valves 77, 77^A and the pipes 78, 78^A carrying the valves 79, 79^A. The pipes 74, 74^A lead to a source of water supply, the pipes 76, 76^A lead to the bottom of the liquid reserve tank 38, which is situated above the pumps 71, 71^A and the pipes 78, 78^A lead to a tank containing the liquid in which the dye is dissolved. Connected with the pumps 71, 71^A 120 125 130

respectively are the two-way pipes 85, 85^A, branching into the pipes 86, 86^A carrying the valves 87, 87^A and opening into the air, and the pipes 88, 88^A carrying the valves 89, 89^A, connected with an exhaust and compression pump not shown. The pumps 71, 71^A are connected with the pipes 90, 90^A carrying the valves 91, 91^A, the pipes 90, 90^A being connected to the top of the reservoir tank 38 10 by the pipes 92, 92^A carrying the valves 93, 93^A.

Situated within each of the members 64, 64^A is a nested series of conical members comprised of the annular members 80, 80^A, 15 supported by the supporting members 81, 81^A, the length of each conical member being somewhat greater than that of the conical member directly within it, as shown in Fig. 4.

20 The operation of the device is as follows, assuming that the dyeing or treating operation has been finished, and the device in the position shown in Figs. 1 and 2: All the valves are closed with the exception of valve 25 84 thus allowing all the liquid contained within the receptacle to drain out. The pipe 35 is then uncoupled. The series of screw-bolts 61, 61, 61^A, 61^A, are withdrawn, the clamping members 59, 59 opened and the 30 gaskets 82, 82 removed, thus freeing the receptacle 23 from engagement with the members 64, 64^A. Truck 20 is then withdrawn from its position between the trucks 56, 56^A by rolling it upon the tracks 22, 22. The 35 receptacle 23 is then given a quarter revolution by turning the wheel 29, and if necessary may be maintained in that position by the screw-bolt 94, the receptacle 23 then being in the position shown in Fig. 3. The 40 series of screw-bolts 69, 69 (Figs. 1 and 2) are then withdrawn from engagement with the lugs 32, 32 and the member 67 withdrawn from within the receptacle 23. The fiber-holding members 46, 45, the member 45 45 103 and the fiber-holding members 44 and 47 are then removed in the order stated by means of hooks inserted beneath the pins 100, 100, in the lugs 49, 49, as illustrated in Fig. 3. When it is desired to load the device with fiber, the fiber-holding member 47 (Fig. 1) is introduced into the receptacle 23, the device being in the position shown in Fig. 3 and fiber introduced therein, or the fiber may be introduced into the member 47 before 55 introduction into the receptacle. The fiber-holding member 44 with the fiber is then similarly placed upon the member 47. The member 103 is then introduced, no fiber being contained therein, and finally the fiber-holding members 45 and 46 with fiber are introduced. The member 67 is then introduced, its lugs 68, 68 abutting upon the lugs 49, 49 of the member 46, and the series of fiber-holding members brought into intimate 60 65 and fixed contact with each other by means

of the screw-bolts 69, 69. The receptacle 23 and its contents are then given a quarter revolution by means of the wheel 29 and its connecting members. The truck 20 with the receptacle 23 is then moved along the tracks 22, 22 until the receptacle is positioned between the members 64, 64^A as shown in Figs. 1 and 2, and the joints between the receptacle 23 and the members 64, 64^A made tight as described above. The pipe 35 is fixedly 70 75 attached to the shell 31. The device is then in the position shown in Figs. 1 and 2.

The dyeing operation is then conducted as follows: Valve 84 is closed and valves 79^A, 91^A and 93 are opened. The pump 71^A is 80 then started, which takes the dye liquor from the dissolving tank, not shown, to which pipe 78^A is attached, through the pipe 78^A and forces it through the various fiber-holding trays 47, 44, 83, 45 and 46 into the pipe 92 85 through which it flows into the reserve tank 38. When all of the liquor from the dissolving tank has been delivered to the pump 71^A, the valve 79^A is closed and the valve 77^A is opened, thus allowing a free circulation of 90 liquor by means of the pump 71^A, from the tank 38, through the device and the fiber contained therein back into the tank 38. If it is desired to reverse the flow of the dye liquor through the device and the fiber, the pump 95 71^A is stopped, valves 77^A and 93 are closed and valves 77, 91 and 93^A are opened and pump 71 started, thus allowing a circulation of the liquor in tank 38, through the pipe 76, the pump 71, the devices and 100 through the pipe 93^A back into the tank 38. If it is desired to pass the liquid from both ends of the device toward the middle and out through the space formed by the member 103, all of the valves are closed with the 105 exception of 77, 91, 77^A, 91^A and 37 and both pumps 71 and 71^A started, the liquor will thus circulate from the tank 38, through both pump 71 and 71^A inwardly through the fiber and back into the tank 38 through the pipe 35. 110

When the dyeing operation is completed the liquor in the dyeing chamber is removed by allowing it to drain through the pipe 83 by closing all the valves with the exception of valve 84 which is opened. 115

If it is desired to wash the goods, valve 84 is closed, water is admitted through the pipes 74, 74^A by opening the valves 75 and 75^A, and the water forced through the device and the goods contained therein, the other valves being in such an open or closed position as to cause the water to enter either through the pipe 74 or 74^A and exit through the other one, the circulation being caused by either the pump 71 or 71^A. 120

If it is desired to treat the dyed fiber with air, the valves 87 and 89^A are opened and the exhaust pump (not shown) started, the other valves being arranged to allow air to be sucked in through the pipe 86, the device and 125 130

fiber, by the suction upon the pipe 88^A, or by using the compression side of the pump (not shown) air may be forced through the device and the fiber in an opposite direction 5 from that just described.

During all of these operations the valves 41 and 41^A are maintained in an open condition, thus allowing the fiber in the smaller device 39 to receive exactly the same treatment 10 as that in the larger device, and the condition of the fiber in the larger device may be determined at any time without interrupting the process by closing the valves 41, 41^A and examining the fiber in the 15 smaller device 39.

One of the chief improvements in my device is the method whereby the dyeing chamber and its contents may be removed from the source of liquid supply without the necessity of handling, or moving the latter, thus 20 effecting a very considerable saving in time of operation and cost of erection.

I do not limit myself to the particular size, shape, number or arrangement of parts 25 as described and illustrated, all of which may be varied without going beyond the scope of my invention as described and claimed.

What is claimed, is:

30 1. In a dyeing machine, in combination, a dyeing receptacle, a series of parallel foraminous plates spaced from each other within the dyeing receptacle, a chamber at each end of the dyeing receptacle and capable of abutment thereon, means for circulating a liquid 35 through the two chambers and the foraminous plates, means for removing the dyeing receptacle from between the two chambers without moving said two chambers, 40 means for revolving the dyeing chamber, and means for removing the foraminous plates from the dyeing chamber.

45 2. In a dyeing machine, in combination, a dyeing receptacle, a series of parallel foraminous plates having divergent shaped openings within the dyeing receptacle, means for maintaining the plates at predetermined distances from each other, a chamber at each end of the dyeing receptacle and 50 capable of abutment thereon, means for passing a liquid through the chambers and the foraminous plates, means for removing the liquid from the dyeing chamber after it has passed through a chamber and some of the 55 foraminous plates, means for removing the dyeing receptacle from abutment with the chambers without moving the chambers and means for revolving the dyeing receptacle.

60 3. In a dyeing machine, in combination, a dyeing receptacle, a series of parallel foraminous plates having oppositely directed rods, means for maintaining the plates at predetermined distances from each other, a chamber at each end of the dyeing receptacle 65 abutting thereon, means for circulating a

liquid through the chambers and the foraminous plates, means for removing the chambers and the dyeing receptacle from abutment upon each other without moving the chambers, means for revolving the dyeing receptacle to allow of the removal of the plates and means for removing the plates. 70

4. In a dyeing machine, in combination, a dyeing receptacle, a series of parallel foraminous plates comprising a series of cylindrical rods having divergent shaped openings between them and extended rod members within the dyeing receptacle, means for maintaining the plates at predetermined distances from each other, a chamber at each 80 end of the dyeing receptacle and capable of abutment thereon, means for passing a liquid through the chambers and the foraminous plates, means for forcing air through the chambers and the foraminous plates, means for removing the liquid from the dyeing chamber after it has passed through a chamber and some of the foraminous plates, means 85 for removing the dyeing receptacle from abutment with the chambers without moving the chambers and means for revolving the dyeing receptacle. 90

5. In a dyeing machine, in combination, a dyeing receptacle, a chamber at each end of the dyeing receptacle and abuttable thereon, means whereby the dyeing receptacle may be moved from abutment with the two chambers without moving the chambers, means for revolving the dyeing chamber, means for forcing a liquid through both 100 chambers into the dyeing receptacle and means for removing the liquid from the dyeing receptacle, a smaller testing device, similar and exterior to the larger device, the two devices being so connected that fiber in the 105 two devices will be treated equally and means for allowing the examination of the fiber in the testing device without interrupting the treatment of the fiber in the other device.

6. In a dyeing machine, in combination, a dyeing receptacle, a series of parallel foraminous plates comprising a series of parallel cylindrical bars having divergent shaped openings between them and extended rods within the dyeing receptacle, means for maintaining the plates at predetermined distances from each other, a chamber at each end of the dyeing receptacle and capable of abutment thereon, means for passing a liquid through the chambers and the foraminous plates, means for forcing air through the chambers and the foraminous plates, means for removing the liquid from the dyeing chamber after it has passed through a chamber and some of the foraminous plates, means 115 for removing the dyeing receptacle from abutment with the chambers, means for revolving the dyeing receptacle, a smaller testing device, similar and exterior to the larger device, the two devices being so connected 120 125 130

that fiber in the two devices will be treated equally by liquid and by air, and means for allowing the examination of the fiber in the testing device without interrupting the treatment of the fiber in the other device.

7. In a dyeing machine, in combination, a dyeing receptacle having a pyramidal shaped flange at each end, a chamber at each end of the dyeing receptacle having a pyramidal shaped flange, means for obtaining and maintaining a tight jointure between the flanges of the dyeing receptacle and the two end chambers, means within the dyeing receptacle for containing fiber, means for removing the dyeing receptacle from engagement with the end chambers, means for revolving the dyeing receptacle, and means whereby a continuous circulation of liquid may be passed through both of the chambers, the dyeing receptacle and fiber contained therein.

8. In a dyeing machine, in combination, a dyeing receptacle having a pyramidal shaped flange at each end, a series of parallel fo-

raminous plates comprising a series of cylindrical rods having divergent shaped openings between them and extended rod members within the dyeing receptacle, means for maintaining the plates at predetermined distances from each other, a chamber at each end of the dyeing receptacle having a pyramidal shaped flange, means for obtaining and maintaining a tight jointure between the flanges of the receptacle and the chambers, means for passing a liquid through the chambers and the foraminous plates, means for forcing air through the chambers and the foraminous plates, means for removing the liquid from the dyeing chamber after it has passed through a chamber and some of the foraminous plates, means for removing the dyeing receptacle from engagement with the chambers without moving the chambers and means for revolving the dyeing receptacle.

Signed at New York city in the county of New York and State of New York this 26th day of March 1917.

HOWARD M. DUDLEY.
